TIMING MECHANISM

Ira E. McCabe, Chicago, Ill.

Original application February 27, 1939, Serial No. 258,591. Divided and this application May 25, 1940, Serial No. 337,154

2 Claims. (Cl. 175—375)

This invention relates to improvements in timing mechanisms for operating an electric switch, and this application is a division of this applicant's prior co-pending application Serial No. 258,591, filed February 27, 1939.

Said parent application, Serial No. 258,591, discloses an electro-thermal motor for actuating a timer mechanism to operate an electric switch normally opened and closed by a remote control, such as disclosed in this applicant's prior Patent No. 2,139,454, December 6, 1938, and a combination of these two devices in such a manner that the timer mechanism is rendered operative only during those periods when the switch is opened by the remote control. This combination produces an improved timing mechanism and is the subject matter of this divisional application.

It is an object of this invention to provide an electro-thermal motor in connection with a timer mechanism to open and close an electric switch, both of which are actuated by a remote control in such a manner that while the switch is opened by the remote control the electro-thermal motor will be rendered operative to alternately close and open the switch independently of the remote control.

With these and other objects in view, reference is made to the accompanying sheets of drawings which illustrate a preferred form of this invention, with the understanding that detail changes may be made without departing from the scope thereof.

In the drawings:

Figure 1 is a view in front elevation of a heat motor constructed in accordance with this invention, with parts broken away and detached from the base or supporting plate.

Figure 2 is a view in side elevation of Figure 1 looking upon the lefthand side thereof.

Figure 3 is a view in side elevation of Figure 1 looking upon the right side.

Figure 4 is a top plan view of the driving mechanism with parts broken away and partly in section.

Figure 5 is a fragmentary detail view in elevation of the electrical resistance heating element.

Figure 6 is a view in front elevation of a practical application of this improved heat motor.

Figure 7 is a wiring diagram of Figure 6.

In the embodiment of this invention, as illustrated in Figures 1, 2 and 3, cylindrical sections 1 and 2 of bi-metallic metal are each provided with a re-entrant portion at one end, each of which is mounted upon oppositely disposed angular end portions of brackets 3 and 4, respec-

tively, said brackets mounted upon the upper portion of a base plate B so that the centers of the respective cylindrical sections lie in the same horizontal plane with their respective adjacent peripheries spaced apart from each other. A floating operating link 5 is provided with an upward projection 6 at one end terminating in an angular extension 7 which is passed through a slot provided therefor in the free end of the cylindrical section 1 and the opposite end of the link 5 is provided with an upward projection 8 adapted to be connected by a hinge 9 to the free end of the cylindrical section 2. The two projections 7 and 8 are so connected and arranged as to support the link 5 in a horizontal position. The link 5 is provided with a depending portion 10 extending below the projection 8, the lower extremity of which supports a heater actuator 11 pivoted at one end to the portion 10. The free end of the actuator 11 mounts a roller 12 and is normally urged in an upward direction by the spring 13, one end of which engages the actuator 11 with the other end anchored upon the portion 10 of the link 5. The roller 12 co-acts with an oscillator 14 carried upon an enlarged portion 15 of a shaft 16 mounted in a bearing therefor in the back plate B. An oscillating heater support plate 17 of insulating material is secured to the enlarged portion 15, which plate is provided with terminal posts 18 and 19 upon the upper side thereof. A flat rectangular electric resistance heater 20 with its flat surface positioned parallel to the surfaces of the cylindrical sections 1 and 2 is supported between the adjacent surfaces thereof by electrical conductors 21 and 22 connected to the opposite ends of the resistance wire 23 of the heater 20. The electrical conductors are preferably covered with insulation and their lower respective ends are connected to the terminal posts 18 and 19 upon the insulated heater actuator plate 17.

The outer end of the shaft 16 is mounted in a bearing therefor in a horizontal front plate 24 spaced apart from the base plate B by studs 25 to lie parallel therewith, as shown in Figures 2 and 3, so that the shaft 16 may be oscillated in the said bearings.

The oscillator 14 is preferably in the form of a threaded pin 26 terminating in a conical end received in the enlarged portion 15 of the shaft 16 to provide for adjustment. The upper end of the pin 26 is provided with a knurled head 27 adapted to be engaged and locked in the adjusted position by the free end of a spring 28 secured to the outer end of the enlarged portion 15 of

the shaft 16. The lower conical end of the actuator 14 is adjusted so that the roller 12 of the actuator 11 will normally engage one conical surface thereof and oscillate the shaft 16 and plate 17 to cause the heater 20 to engage the adjacent surface of one of the cylindrical bi-metallic sections of the thermal members. The terminal posts 18 and 19 pass through the plate 17 of insulating material and are connected to a source of electricity by conductors 29. When the current passes from the source through connectors 29, terminal posts 18 and 19, conductors 21 and 22 and resistance wire 23 of the heater 20, and the heater is in the position shown in Figure 1, it will cause the adjacent cylindrical section 1 of the thermal member to reduce in cylindrical form, thus moving the free end downwardly and inwardly, which will cause the floating lever 5 to be rotated about its hinge connection 9 with the other thermal member 2 and thereby cause the heat actuator 11 to move toward the right causing the roller 12 to travel down the conical termination of the oscillator pin 26 to ride over the apex thereof. The tension of the spring 13 as the roller rides over the apex will cause the roller to travel upwardly over the opposite conical side of the pin 26 which will impart a rotation to the shaft 16 causing the heater support plate 17 to oscillate the heater 20 and bring it into contact with the thermal member 2. When the heater 20 contacts the adjacent surface of the thermal member 2, the thermal member 2 will be heated to impart a reverse movement to the floating link 5 to cause the actuator 11 to travel in the opposite direction over the conical surface and apex of the oscillator 14 to impart a reverse oscillation to the heater 20. With the alternate heating of the thermal members one member when heated will be assisted by the other member while cooling whereby the combined moving force of both elements is applied to the floating lever 5 in moving it and an oscillating movement will be imparted to the heater 20 through the reciprocal movement of the floating link 5 as long as the resistance element 23 of the heater 20 is energized.

The floating link 5 is provided with two spaced apart depending similar operating members 30 and 31 adapted to receive in sliding engagement between them a stud 32 carried upon a reciprocating cradle 33. The opposite ends of the cradle 33 are pivotally mounted upon shafts 34 and 35, each of which shafts are supported by a pair of links 36 and 37, the lower ends of which are pivotally mounted upon studs 38 and 39, mounted between the base plate B and front plate 24; each pair of links being connected intermediate their length by spacing members 40. By this construction, when the oscillating heater causes the thermal members 1 and 2 to impart an oscillating movement to the floating link 5, this movement through the operating members 20 and 31 will transmit a reciprocating movement to the cradle 33.

A shaft 41 is received within a hub, mounted upon a ratchet wheel 43 in any desired manner to be rotatable therewith. The ratchet wheel 43 is located between the base plate B and cradle 33 with the hub passing through a bearing 42 provided therefor in the base plate. The reciprocating movement of the cradle 33 is transmitted to the ratchet wheel 43 to impart a rotation to the shaft 41 by pawls 44 in the form of flat springs each having slots 45 adjacent their free end adapted to cause the body of the spring ad-

jacent the free end to form a pawl to engage the ratchet teeth of the ratchet wheel 43 on opposite sides of the shaft 41. The end of the upper spring pawl 44 opposite the slot 45 is secured to the upper end of a portion 46 of the cradle 33 extending upwardly therefrom above the pivot 35 and the corresponding portion of the lower spring pawl 44 is secured to a portion 47 of the pawl 33 depending below the pivot 34 and cut out to provide clearance for the spacer 40.

By this arrangement, the pawls 44 are always in engagement with the teeth of the ratchet wheel 43. Movement of the cradle to the right imparts a clockwise rotation to the ratchet wheel by the upper pawl 44 while movement of the cradle 33 to the left continues the clockwise rotation of the ratchet wheel by the movement of the lower pawl 44. While one pawl imparts movement to the ratchet wheel the other pawl travels over the ratchet teeth.

By providing the ratchet wheel 43 with fine teeth and synchronizing the movement of the elements 1 and 2, a continuous or substantially continuous rotation may be imparted to the shaft 41. In order to synchronize the movements of the free ends of the elements 1 and 2, it is preferable to provide an adjustment for one of the elements. As shown in Figure 1, the bracket 4 is made adjustable so that the thermal element 2 may be adjusted in a vertical direction. The bracket 4 is provided with a right angular extension 48 which receives an adjusting screw 49 mounted in a bracket 50 secured to the base plate B. The bracket 4 is also provided with a vertical slot through which a clamp screw 51 passes and by means of which the bracket may be secured in position after adjustment. Should the movement of the two thermal elements differ slightly when heated, the element 2 may be raised or lowered to adjust the relationship of the heater actuator roller 12 to the oscillator 14 for each element. Therefore, the heating effect of the heater on each element may be timed to cause each element, when heated, to apply the same degree of rotation to the ratchet wheel 43 and since the oscillator 14 is adjustable the heating periods may be determined to regulate the number of degree rotation which may be imparted by the thermal members for each cycle of operation thus providing a certain desired rotation of the wheel 43 over a desired period of time.

Figure 6 is an illustration of a practical application of the heat motor disclosed in Figures 1 to 5, inclusive; Figure 7 is a wiring diagram of the apparatus shown in Figure 6. The apparatus shown in Figure 6 is a timer mechanism disclosed in detail in this applicant's prior Patent No. 2,139,454, granted December 6, 1938. This mechanism is designed particularly as a timing device for use in connection with other devices for controlling the operation of an electrically operated and controlled coal stoking mechanism for domestic and industrial plants. In Figure 6, the mechanism is shown mounted upon a panel 52, and the timing mechanism is enclosed in a casting 53 mounted upon a base plate B², which corresponds to the base plate B of the heat motor hereinbefore described, and is spaced apart from the panel 52. In the abovesaid Letters Patent, rotation was imparted to the operating shaft of the timing mechanism by a self-starting synchronous motor mounted upon the back of the base plate B². In this application of the heat motor heretofore described and illustrated in Figures 1 to 5, inclusive, the shaft 41 corre-

sponds to the operating shaft of the timing mechanism. In the wiring diagram shown in Figure 7, the mechanism mounted on the panel 52 is shown as applied to the control of a stoker motor in which the commercial line is indicated by the reference letters L—L'. The wire L is connected to the binding post 54 and the wire L' to binding post 55. Binding post 54 is connected to one side of a stationary primary coil PC of a repulsion type relay R, the other side of which is connected through binding post 57 and thence to binding post 55. The windings of the secondary coil SC of the relay R are connected to binding posts 58 and 59 which in turn are connected to a room thermostat T. A motor switch MS operated by the relay, normally open when the relay is de-energized, is connected to binding posts 54 and 56, the latter serving also as a terminal for one connection to a motor M. The other connection from the motor M is connected to binding post 57. When the secondary circuit is open through the room thermostat T, the secondary coil SC is de-energized and falls to rest upon the top of the primary coil PC. When the room thermostat closes the secondary circuit, the secondary coil is energized and is repelled to float above the primary coil PC. This floating movement is employed to close the motor switch MS so that when the motor switch is closed, the current will pass from binding post 54 through the motor switch, binding post 56 through the stoker motor M to the binding post 57 and from this point to binding post 55.

The timing mechanism mounted in the casing 53 includes a cam assembly 60 rotated by the shaft 41; a cam lever 61 mounting a pin 62 to ride over the surfaces of the cam 60 under tension of the spring 63; and an actuating lever 64 pivotally mounted upon the cam lever 61 so arranged as to be moved about its pivot as the cam lever 61 drops into a notched portion of the cam 60 to cooperate with a strip 65 extending from the upper surface of the secondary coil SC of the relay, whereby when the actuating lever 64 is swung to the left, it causes the secondary coil to rotate upwardly about the pivot 66 to close the motor switch MS, as shown in Figure 6. The end of a lever 67 is illustrated for positioning parts of the timing mechanism, not shown, to determine the duration of time the lever 64 may hold the motor switch closed, as disclosed in said Patent No. 2,139,454.

In the timer mechanism illustrated and described in said Patent No. 2,139,454, a constantly energized self-starting synchronous electric motor is employed to operate the timer mechanism.

The timing mechanism is designed for the purpose of controlling the operation of a motor operated stoker, to supply coal at periodic intervals, to maintain the fire during the time the room thermostat is not calling for heat.

This invention contemplates the application of the electrically actuated heat or electro-thermal motor, disclosed herein, to a motor operated timing device of the type disclosed in the aforementioned patent in such a manner that only during those periods when the thermostat is not calling for heat is the timing device rendered operative. This is arranged by establishing a cooperative relationship between the motor switch relay and electro-thermal motor whereby a low voltage circuit may be established from the relay for operating the electro-thermal motor when the thermostat is not calling for heat and whereby a call for heat from the thermostat will operate the

relay to close the motor switch and render the electro-thermal motor inoperative as long as the thermostat circuit remains closed. When the electrically actuated heat or electro-thermal motor, as above described, is connected in circuit with the mechanism illustrated in Figure 6, in the manner shown in the wiring diagram of Figure 7, it is seen that the heating element 23 is always connected through terminal posts 18 and 19 and conductors 29 to binding posts 58 and 59 so that when the room thermostat T is open, or not calling for heat, the heater 23 will be in circuit with the windings of the secondary coil SC and as the primary coil PC is always connected in circuit with the source of electricity a current will be induced in the secondary coil which, when the room thermostat is closed, normally repels the secondary coil to close the motor switch MS. In this application of the electro-thermal motor the electrical resistance 23 is designed so that the heater interposes sufficient resistance in the circuit of the secondary coil, when the room thermostat is open, to prevent the repulsion of the secondary coil and thereby when the room thermostat is open the electric heat motor will be operated to actuate the timing mechanism. When the room thermostat closes its circuit through binding posts 58 and 59 to the secondary coil it will short-circuit the electro-thermal motor and render the same inoperative and thus preserve the resistance heater 23 by limiting its operation to those periods when the circuit to the room thermostat is open. As in common practice, a boiler control BC is interposed in the line L, as shown in Figure 7, to prevent operation of the stoker when conditions within the boiler do not warrant it.

While this application of the heat or electro-thermal motor is described in connection with the timing mechanism disclosed in said Patent No. 2,139,454 as applied to an electrically operated and controlled stoker mechanism, it is obvious that the heat motor may be similarly operated by remote control other than a room thermostat and the opening and closing of the motor switch may be employed to control the operation of a motor for purposes other than the operation of a coal stoker mechanism.

What I claim is:

- 50 1. In a circuit controller, an electric switch in the circuit to be controlled, electrical means for operating said switch comprising a coil movable over a metal core, a circuit including said movable coil, a stationary coil mounted upon the core adapted to be connected in circuit to a source of electricity to induce a low voltage circuit in the movable coil and repel said coil when the circuit through the movable coil is closed, means operating the electric switch in response to the movement of the movable coil, a control device in the movable coil circuit in combination with means to mechanically actuate the movable coil, timing mechanism for periodically actuating the mechanical means, a thermal-electro heat motor for operating the timing mechanism having an electrical resistance heating element connected in the movable coil circuit in parallel to the control device, said heating element, when the control device is in open circuit position, energized to operate the heat motor, said heating element limiting the current flow through the movable coil to prevent the electrical repulsion thereof, said heating element being shunted and rendered inoperative upon the closure of the control de-
- 55
- 60
- 65
- 70

vice circuit to cause the electrical repulsion of the movable coil.

2. In a circuit controller, an electric switch in the circuit to be controlled, electrical means for operating said switch comprising a coil movable over a metal core, a circuit including said movable coil, a stationary coil mounted upon the core adapted to be connected in circuit to a source of electricity to induce a low voltage circuit in the movable coil and repel said coil when the circuit through the movable coil is closed, means operating the electric switch in response to the movement of the movable coil, a control device in the movable coil circuit in combination with means to mechanically actuate the movable coil, timing mechanism for periodically actuating the mechanical means, a thermal-electro heat motor for operating the timing mechanism including two spaced apart coils of thermal metal each hav-

ing one end thereof fixed, a movable electrical resistance heating element arranged between the coils mounted to heat alternately the respective coils, an operating shaft connected to the timing mechanism, transmission means for transmitting the movement of the free ends of the thermal elements to the shaft and additional means actuated by said transmission means for moving the heating element, said element connected in the movable coil circuit in parallel to the control device to be energized when the control device is in open circuit position, said heating element limiting the current flow through the movable coil to prevent the electrical repulsion thereof, said heating element being shunted and rendered inoperative upon the closure of the control device circuit to cause the electrical repulsion of the movable coil.

IRA E. McCABE.
